UNITED STATES PATENT OFFICE.

WILLIAM O. WETMORE, OF THE UNITED STATES ARMY, HONOLULU, TERRITORY OF HAWAII.

OIL LIBERATOR.

Application filed February 10, 1926. Serial No. 87,476.

This invention appertains to novel means for supplying oil to ponds, pools, streams and other waterways for killing mosquitoes in development stages thereby forming an effective mosquito control.

The primary object of the present invention is to provide novel means for supplying oil by the submersion system to waterways for mosquito control in contra-distinction to the spray or dip system which necessitates the use of complicated and expensive apparatus.

Another object of the invention is to provide novel means for slowly liberating oils or other liquids for oiling the surface of waterways, for killing mosquitoes in the development stages embodying an oil container with means for holding the container submerged below the surface of the water, the container having formed therein means for permitting the liberation of the oil or other liquid in the desired quantity.

A further object of the invention is the provision of novel means for associating a weight with a pyramidal shaped oil container whereby the container will be normally held in an upright position and submerged below the surface of the water, the apex of the pyramidal container having means for permitting the liberation of the liquid therefrom.

A still further object of the invention is to provide a novel anti-mosquito breeding liquid dispenser of the submerged type which will be durable and efficient in use, one that will be simple and easy to manufacture, and one which can be placed upon the market at a reasonable cost.

With these and other objects in view, the invention consists in the novel construction, arrangement, and formation of parts as will be hereinafter more specifically described, claimed and illustrated in the accompanying drawings, in which drawings:

Figure 1 is a side elevation of the novel device in use, parts of the same being shown broken away and in section,

Figure 2 is a top plan view of the improved device,

Figure 3 is a bottom plan view thereof illustrating the means of associating the weight therewith,

Figure 4 is a side elevation of the improved device illustrating how the same can

be used in the drip method of supplying oil to the surface of a waterway,

Figure 5 is a side elevation illustrating the further method of the use of the improved device,

Figure 6 is a central vertical section through a modified form of the apparatus,

Figure 7 is a horizontal section through the same taken on the line 7—7 of Figure 6 looking in the direction of the arrows,

Figure 8 is a central vertical section through the upper end of the device showing a modified form thereof.

Referring to the drawings in detail, where-in similar reference characters designate corresponding parts throughout the several views, the letter A generally indicates the improved mosquito control apparatus of the submersion type, which has been found in actual use to possess numerous advantages over a spray or drip type of oiling apparatus. In use of the spray or drip type of oiling apparatus, not only is a complicated apparatus necessary to accomplish the purpose intended, but it has been found that the oil has a tendency to break up in small quantities and float in patches on the water and a relatively long length of time is necessary to consume the operation.

In the submersion type as shown in the present application the oil is liberated in bubbles and floats from the surface thereof and spreads in a uniform sheet over the water.

As shown in Figures 1 to 3 inclusive, the device embodies a pyramidal shaped oil container 10 which can be made in any desired size for holding the desired quantity of oil. The extreme upper end of the container 10 can be provided with a U-shaped strap or clevis 11 to facilitate the handling thereof and in order to hold the container 10 submerged below the level of the waterway with which the same is associated in an upright position, a weight 12 is connected with the extreme lower end thereof. This weight 12 can be of any preferred character and can be connected with the body in any desired way.

In order to eliminate the necessity of shipping a heavy weight with the container 10, a box 13 is provided which forms a base for the container. As shown this box 13 embodies a flat bottom wall 14 and upwardly

extending relatively short side wall 16. The upper end of the box 13 is left open and when the device A is to be used, the said box is filled with sand or other heavy material to form the weight. In the drawings depending straps 16 are riveted or otherwise secured to the side walls of the oil container 10 for engaging the side walls 15 of the box and the lower ends of these straps are provided with hooks 17 for engaging the bottom wall of said box for holding the same firmly in place.

In accordance with the invention, the upper end of the container is provided with an oil outlet 18 of the desired size and a water inlet 19 in one side wall adjacent to the bottom thereof.

In actual practice the apex of the container 10 can be closed as well as the opening 19 and these places are marked to permit the desired sized openings to be formed therein, when the device is to be used.

In use of the improved device the same is thrown or pitched into the waterway at an advantageous point and it can be seen that the oil will rapidly flow to the surface of the stream or waterway and cover the surface thereof and thus prevent the breeding of the mosquitoes.

In Figure 4 of the drawings, I have shown another method of using the device A and in this method the weight can be dispensed with and the bottom wall of the container is provided with a pivoted eye 20 which is adapted to receive a hook 21 formed on an arm 22. This arm 22 is formed on or carried by a suitable post 23 and by this construction it can be seen that the container A is held in an elevated position with the apex thereof lowermost which allows the oil or other liquid to drip from the container on the surface of the water. It is preferred however to use the container as the submersion type, as such results can be obtained from such use, but I have shown in Figure 4 the method of using the container by allowing the oil to drip therefrom, so that the container can be used under all conditions, such as in low marshy land.

In Figure 5 of the drawings I have shown still another method of using the device and this method can be employed when the waterway is of a deep character.

In this method the weight 12 is employed and a suitable rope or cable 25 is tied to the strop or shackle 11 and then to a suitable float 26, which can be a dead log or the like as shown in the drawings.

In Figures 6 and 7, I have shown a slightly modified form of the invention which is generally indicated by the reference character B. In this form I also provide a pyramidal shaped container 30, the apex portion of which is provided with an outlet spout 31 which can be threaded for the re-

ception of a cap or the like 32. As shown the cap 32 is provided with a carrying ring 33. The container 30 adjacent to the lower end thereof is provided with a filling spout or the like 34 by means of which the oil or other liquid can be poured into the container and this spout is closed by a cap 35. When the device is in use the caps 32 and 35 can be removed in order to allow the exit of the oil or other liquid and the entrance of water into the same to displace the oil.

In order to hold the container submerged in the body of water and in an upright position, a partition 36 is placed in the container adjacent to the lower end thereof defining a compartment 37 which can be filled with a suitable material of a heavy character, such as sand or the like. The bottom wall of the container 30 is also provided with a filling spout 38 which communicates with the compartment 37 and permits the introduction of sand or other heavy material into the same. This spout is also closed by a suitable cap 39. The bottom wall of the container can also be provided with a suitable eye 40 for facilitating the manipulation of the device.

If desired the partition 36 can be provided with a central group of openings 41 so as to allow communication to be had between the body of the container and the compartment 37. In Figure 8 of the drawings, I have shown another slightly modified form of the invention in which a wick 50 can be utilized for dispensing oil from the container to the water. As shown the wick 50 extends through a suitable opening 51 formed at the apex of the container 52 which can be of the same type as the containers shown in the previous form.

From the foregoing description, it can be seen that I have provided a novel means for supplying oil or other liquid by the submersion method to a waterway for effectively preventing the breeding of mosquitoes.

Changes in details may be made without departing from the spirit or the scope of this invention, but:

What I claim as new is:—

1. A device for preventing the breeding of mosquitoes, a liquid receiving container gradually converging toward one end and provided with a liquid outlet opening at said end and means for associating a weight with the face of the container including a compartment for the reception of a heavy granulated material.

2. In a device for preventing the breeding of mosquitoes, a liquid receiving container gradually converging toward one end, said end being provided with a liquid outlet opening, a box for the reception of a heavy material for association with the enlarged end of the container and means detachably connecting the box with the container.

3. In a device for supplying oil and other anti-mosquito breeding liquid to waterways by the submersion method, a container gradually converging toward one edge having a 5 liquid receiving outlet formed therein, the container adjacent to the opposite end having a water inlet opening formed therein, a box for the reception of a heavy granulated material detachably associated with the end of 10 the container remote from the outlet end thereof, and handles associated with the container.

4. A device for preventing the breeding of mosquitoes comprising a submergible pyram-

idal shaped container having an outlet opening in the upper end thereof and a water inlet opening adjacent to the opposite end thereof, means for closing the openings when the container is not in use, a partition disposed within the container adjacent to the 15 base thereof defining an anti-breeding mosquito liquid compartment and a heavy granulated material receiving compartment, means for filling the last mentioned compartment with heavy material, and manipulating 20 handles associated with the container.

In testimony whereof I affix my signature.

WILLIAM O. WETMORE.
